UNITED STATES PATENT OFFICE.

PHILIP T. DODGE, OF NEW YORK, N. Y., ASSIGNOR TO MERGENTHALER LINOTYPE COMPANY, A CORPORATION OF NEW YORK.

TYPOGRAPHICAL MACHINE.

1,139,020.

Specification of Letters Patent. Patented May 11, 1915.

Application filed February 6, 1915. Serial No. 6,590.

To all whom it may concern:

Be it known that I, PHILIP T. DODGE, a citizen of the United States, residing at New York, in the county of New York and State of New York, have invented certain new and useful Improvements in Typographical Machines, of which the following is a specification, reference being had thereto in the accompanying drawing.

10 My invention relates to typographical machines, such as linotype machines of the general organization represented in Letters Patent of the United States, No. 436,532 to O. Mergenthaler, wherein circulating matrices are released from a magazine in the order in which their characters are to appear in print and then assembled in line, the composed line transferred to the face of a mold, the mold filled with molten metal 20 to form a slug or linotype against the matrices which produce the type characters thereon, and the matrices thereafter elevated and returned through a distributing mechanism to the magazine from which they started. More particularly, it relates to that class of machines equipped with a plurality of magazines and a plurality of distributors, such as permit the mixture of different fonts or faces in the same line, and 25 the return of the matrices to their proper magazines simultaneously.

It is one of the principal objects of my invention to provide a machine of this character, wherein a single stationary bank of 35 escapements may be employed to control the release of the matrices from one or another of the magazines, so as to secure the many advantages arising from such construction. The manner in which this object is attained 40 will be fully explained in the detailed description to follow and finally pointed out in the claims.

In the accompanying drawings, I have shown my invention in preferred form and 45 by way of example, and as applied to a machine of the class stated, but obviously many changes and variations may be made thereon, and in its mode of application, which will still be comprised within its spirit. 50 Thus, it may be adapted to other forms of typographical machines, such as type-setters, type-casters and the like, which handle type or dies instead of matrices. Generally speaking, I desire it to be understood that

I do not limit myself to any specific form 55 or embodiment, except in so far as such limitations are specified in the claims.

Referring to the drawings: Figure 1 is a side elevation of a portion of a linotype machine, having my invention applied thereto; Figs. 2 and 3 are similar views showing the parts in different position; Fig. 4 is a detail; Fig. 5 is a plan view of the magazine supporting frame; and Fig. 6 is a section taken on the line 6—6 of Fig. 3. 65

The matrices X are stored according to font in the magazines A and B, which are connected, by means of the channel-entrances C and D, to the two distributors E and F respectively, the matrices being delivered to the latter by the tubes G leading from the font separator H. The parts so far described, except as hereinafter pointed out, are or may be of any well-known construction, such, for instance, as illustrated 70 in United States Letters Patent No. 848,771, to John R. Rogers.

According to my invention, the two magazines A and B are mounted in a swinging supporting frame J, which is pivotally connected to the machine frame, as at J¹, so as to bring one or another of the magazines into registration with a fixed assembler entrance K. The lower magazine B is mounted directly upon the supporting frame J, 85 while the upper magazine A is mounted upon its customary base frame A¹, which is pivotally connected at its upper end, as at J² (Fig. 1) to the supporting frame, and which rests at its lower end upon the upper 90 side of the magazine B. The swinging of the frame J is effected by means of a pair of cams P, arranged in engagement with rollers J³ (see Fig. 5) on opposite sides of the frame, and fast upon a transverse rock 95 shaft P¹ mounted to turn in bearings in a pair of supporting arms P², which are pivotally connected at their rear ends to a transverse rod P³ and at their forward ends rest upon adjusting screws P⁴ in the framework. 100 The shaft P¹ is provided with an operating handle R for turning the cams in one direction or the other to raise and lower the magazines, as required. It will be noted that the pivotal point J¹ of the frame J is 105 located close up to and between the two distributors E and F, in such manner as to avoid any appreciable movement of the

channel entrances C and D, when the frame is swung up and down, and thus to maintain their operative relation to the distributors.

Arranged behind the assembler entrance 5 K is a stationary bank of escapements M, each comprising, as usual, a pivoted lever and two matrix releasing pawls, which are moved back and forth by suitable actuating means controlled from the keyboard (see 10 dotted lines in Fig. 1). The several magazines are each formed in their underside faces with openings N to receive the escapement pawls, and are so arranged in the supporting frame J that one or another may 15 be brought into operative relation to the bank of escapements at will.

Referring to Figs. 1 and 2, it will be observed that the upper magazine A projects forwardly and beyond the magazine B and 20 overhangs it to a considerable extent, so that the same movement of the supporting frame J, that shifts it into registration with the assembler entrance K, also effects the engagement of the escapements M with the 25 openings N in its under side. In other words, the manipulation of the handle R alone is sufficient either to elevate the magazine A to inactive position, as shown in Fig. 2, or to lower it to active position as 30 shown in Fig. 1, at which latter time it is brought automatically into operative relation to the escapements. The mode of bringing the lower magazine B into action and into operative relation to the escapements 35 is somewhat different, and involves not only its vertical shifting, but also its forward movement with relation to the magazine A, and the supporting frame J. By the manipulation of the handle R, and through the 40 instrumentality of the cams P, the supporting frame J is first elevated to the position indicated in Fig. 2; the magazine B is next moved forward into engaging relation to its escapement M, as indicated by dotted 45 lines in Fig. 2; and the supporting frame is then lowered slightly to bring the magazine down upon the escapements and effect their engagement in its openings N, as shown in Fig. 3. When it is desired to 50 shift the magazine B out of action, the reverse operation is performed, namely, the supporting frame J is slightly raised to free the magazine from the escapements, and the magazine is then moved rearwardly to 55 its original position, and if it then be desired to bring the magazine A into operation, this is done by merely lowering the frame J by the handle R. In order to 60 lower and raise the supporting frame J to the slight extent necessary to effect the engagement and disengagement of the magazine B with and from the escapements M, the cams P are formed with notches or depressions P⁵ in which the rollers J³ engage, 65 when the supporting frame J is elevated to

the required extent and after the magazine B is moved to its forward position therein. This will be described more fully at a later point. The longitudinal movements of the magazine B just described may be controlled manually if desired, but I prefer to effect them mechanically and automatically. To this end, I provide the shaft P¹ with 70 a pair of arms P² (one being integral with the handle R), which are connected by 75 means of links S to the opposite ends of a transverse bar or rib B¹ fixed to the under side of the magazine. The links S are provided at their points of connection to the bar with small rollers S¹ (see Fig. 5), which 80 are adapted to ride upon upright tracks P³ projecting from the arms P². As a result of this arrangement, the continued rotation of the handle R will not only effect the elevation of the frame J, but in addition will 85 automatically shift the magazine B longitudinally with reference thereto as next to be described.

The operation of the parts is as follows:— Starting from the position shown in Fig. 1, 90 the handle R is moved in the direction indicated by the arrow, causing the rotation of the cams P and the elevation of the frame J to the position shown in Fig. 2. During this movement, the rollers S¹ maintain their 95 engagement with the tracks P³ and thus prevent the endwise movement of the magazine B. When, however, the handle is moved farther, as indicated by the arrow in Fig. 2, the rollers S¹ are raised above the 100 tracks P³, and the links S are caused to shift the magazine forwardly to the position shown by dotted lines in Fig. 2, the movement of the magazine being limited by the engagement of its rib B¹ with the 105 standing shoulders J⁴ on the frame J (see Figs. 3 and 5). It is pointed out that the portions of the cams P active during this second range of movement are concentric so as not to interfere with the position of 110 the supporting frame J. Finally, the handle is moved slightly farther, to bring the notches P⁵ of the cams P into engagement with the rollers J³ on the supporting frame, and thus to allow the latter to be lowered 115 to effect the engagement of the escapements M in the openings N of the magazine B, as shown in Fig. 3. When it is desired to bring the upper magazine A into action, the handle R is moved in the reverse direction, 120 as shown by the arrow in Fig. 3, its continued movement acting first to raise the frame J slightly to disengage the escapements from the magazine B, then to shift the latter longitudinally with reference to 125 the frame and back to its original position therein, and finally to lower the frame to seat the magazine A upon the escapements. It will be understood that during these various operations the distribution of the mat- 130

ries should not be interrupted. I therefore provide the channel entrance D with a relatively movable section D¹ (Figs. 4 and 6), which is attached to the magazine B by a latch T so as to be movable longitudinally therewith. The section D¹ comprises a plate D² and a series of partitions d¹ which engage in slots in the back plate of the entrance D and register with its customary partitions d. It will be noted that the partitions d¹ are of such length that they will register with and form continuations of the partitions d in either of the longitudinal positions of the magazine B.

Both the entrances C and D are carried by a supporting frame U, which is pivotally connected to the frame J, as at U¹, so as to be swung downwardly to give access to the distributors and the magazines, as shown by dotted lines in Fig. 3. The frame U is formed with grooves or guideways U² to receive tongues d² of the section D¹, so as to permit the latter to slide forwardly and backwardly therein as the magazine B is moved longitudinally. It will be understood, of course, that when the entrances are swung downward away from the magazines, the latch T should first be disengaged from the magazine B. A detent T¹ (see Fig. 6) may be used to hold the section D¹ in place in the frame U when it is swung downward. Since the magazines are without escapements, some suitable mechanism should be employed to prevent the escape of matrices therefrom, when not in action. In the drawings, I have shown for this purpose the well-known locking rock shafts O, which may be operated in any desired manner, as will be familiar to those skilled in the art.

As previously stated, I have shown my invention only in preferred form and by way of example, and it is obvious that many modifications or alterations therein will suggest themselves to those skilled in the art without departure from its scope.

Having thus described my invention, its construction and mode of operation, what I claim and desire to secure by Letters Patent of the United States is as follows:

1. In a typographical machine, the combination of a single series of escapements, a plurality of magazines, each provided in one of its faces with openings to receive the escapements, and movably arranged so that one or another may be brought into operative relation thereto, and a corresponding plurality of distributors to coöperate with the magazines.

2. In a typographical machine, the combination of a single series of escapements, a movable supporting frame, a plurality of magazines mounted therein, and one movable longitudinally relatively thereto into and out of engaging relation to the escape-

ments, and a corresponding plurality of distributors to coöperate with the magazines.

3. In a typographical machine, the combination of a single series of escapements, a plurality of magazines movable as a whole and also relatively to each other to bring any selected one into operative relation to the escapements, and a corresponding plurality of distributors to coöperate with the magazines.

4. In a typographical machine, the combination of a single series of escapements, a plurality of magazines, a supporting frame therefor movable to locate a selected magazine above or below the level of the escapements, the said magazine being movable forwardly and backwardly in the frame into and out of engaging relation to the escapements, and a plurality of distributors to coöperate with the several magazines.

5. In a typographical machine, the combination of a single series of escapements, a plurality of magazines, a movable supporting frame therefor, the said magazines being arranged in said supporting frame so that one may be moved thereby directly into and out of operative relation to the escapements, and a plurality of distributors to coöperate with the several magazines.

6. In a typographical machine, the combination of a single series of escapements, a plurality of magazines, a movable supporting frame therefor, the said magazines being arranged in overlapping relation in their supporting frame, so that a forward magazine may be moved directly thereby into and out of operative relation to the escapements, and a rear magazine being slidably arranged in the frame so as to be movable forwardly and backwardly into and out of engaging relation to the escapements, and a plurality of distributors to coöperate with the several magazines.

7. In a typographical machine, the combination of a single series of escapements, and a plurality of magazines, one being arranged to move vertically directly into operative relation to the escapements, and another being arranged to move both vertically and endwise into engaging relation thereto, and a plurality of distributors to coöperate with the several magazines.

8. In a typographical machine, the combination of a single series of escapements, a plurality of magazines each provided in one of its faces with openings to receive the escapements, and a plurality of distributors, one for each magazine, the said magazines being movably arranged so that one or another may be engaged with the escapements without disturbing their operative relation with the distributors.

9. In a typographical machine, the combination of a distributor, a series of escapements, a magazine operatively connected

with the distributor, and a supporting frame for the magazine, the said magazine being movable longitudinally relatively to its supporting frame into and out of engaging relation to the escapements without disturbing its operative connection with the distributor.

10. In a typographical machine, the combination of a longitudinally movable magazine, a distributor, and a channel entrance for conducting the type or matrices from the distributor to the magazine, the said entrance being formed with a relatively movable section connected to the magazine so as 15 to be movable therewith, for the purpose described.

11. In a typographical machine, the combination of a single series of escapements, a plurality of magazines, a movable supporting frame wherein they are mounted, means for moving the frame, and means controlled by the movement of said frame for shifting one of the magazines longitudinally relatively thereto into and out of engaging relation to the escapements.

12. In a typographical machine, the combination of a single series of escapements, a plurality of magazines, a movable supporting frame wherein they are mounted, 20 means for moving the frame, and means con-

nected to said moving means for shifting one of the magazines longitudinally relatively to the supporting frame into and out of engaging relation to the escapements.

13. In a typographical machine, the combination of a single series of escapements, a movable supporting frame, a magazine mounted thereon, and means whereby the movement of the supporting frame will shift the magazine longitudinally into and out of engaging relation to the escapements. 35

14. The channel entrance D formed with partitions d and having the relatively movable section D' formed with partitions d' 40 registering with the partitions d. 45

15. In a typographical machine, the combination of assembling devices, a plurality of magazines, one arranged to move vertically directly into and out of operative relation to the assembling devices and another being arranged to move both vertically and endwise into and out of operative relation thereto, and a plurality of distributors, one for each of the magazines. 50

In testimony whereof, I have affixed my signature in presence of two witnesses.

PHILIP T. DODGE.
